United States Patent Office.

SUMNER PACKARD, OF GRAFTON, MASSACHUSETTS.

Letters Patent No. 99,466, dated February 1, 1870

IMPROVEMENT IN BOOT AND SHOE-SHAVES.

The Schedule referred to in these Letters Patent and making part of the same.

To all whom it may concern:

Be it known that I, SUMNER PACKARD, of Grafton, in the county of Worcester, and Commonwealth of Massachusetts, have invented certain new and useful Improvements in Boot and Shoe-Shaves; and I do hereby declare that the following is a full, clear, and exact description of the same, reference being had to the accompanying drawings, forming a part of this specification, in which—

Figure 1 represents a bottom view of my improved boot and shoe-shave;

Figure 2 represents a top view of my improved boot and shoe-shave;

Figure 3 represents a front view of the same; and

Figure 4 represents a transverse central section, on line A B, fig. 2.

To enable those skilled in the art to which my invention belongs, to make and use the same, I will proceed to describe it more in detail.

The nature of my invention consists,

First, in the combination, with the blade, of conical-pointed adjusting-screws, as hereafter explained.

Second, in the combination with the shanks of the blade, of holding-screws, arranged in the front of the handle, as hereinafter described.

Third, in the combination with the handle of the shave, of a guard-plate and blade, and devices for adjusting the same, as and for the purposes hereinafter explained.

Fourth, the combination with the blade and handle, of a back rim, as and for the purposes stated.

In the drawings, the part marked A is the handle, and B is the blade, inserted in a recess formed in the handle A, as indicated in the drawings.

The shanks a, of the blade B, project out past the ends of the blade, and are then turned up, so as to fit slots in the handle A.

A rim, C, is formed at the back of the blade B, against which the latter rest, and conical-pointed screws, c, are arranged through said rim, with their conical points passing over the reinforce or flange b, at the back of the blade B, in such a manner that when the screws c are run in, the blade is forced down by the conical points pressing upon the reinforce b.

In this way the blade B can be very nicely and accurately adjusted, to remove any thickness of shaving desired, and when the screws are once properly set they do not require to be changed when the blade B, is removed for sharpening, consequently no time is lost or taken up in readjusting the blade, as is the case with the shave as ordinarily constructed.

The blade is held securely in any adjusted position, by means of screws d, that pass through the handle A, from the front side, and press against the front of the shanks a, as indicated by dotted lines in fig. 2 of the drawings.

By arranging the holding-screws d so as to be in-

serted from the front of the handle, sufficient thickness of metal is obtained to receive the entire length of the screw-threads, while at the same time the pressure is thrown against the shanks a, in such a manner as to keep the edge of the blade B to the work.

By this arrangement, also, the back of the blade B takes its bearing directly from the handle, whereby it is always held square, and is not liable to cant, when in use, as it is when the back is supported by the points of screws.

An adjustable guard-plate, E, is arranged on the under side of the handle A, in front of the blade B, and said plate is held in place by a clamp-screw, f, which passes through a transverse slot, e, in the handle A, and by loosening said screw f, the guard-plate E can readily be moved back, to compensate for the wearing away of the blade B, as occasion may require, thus preserving their relative distance apart until the plate is completely worn out.

Those skilled in the art will readily appreciate the practical importance and value of the conical-pointed adjusting-screws c, since they enable the operator to remove the blade for grinding or sharpening, and replace the same very quickly, in the exact position which it before occupied, so that it will cut the same depth of shaving that it cut before it was removed.

Any desired size of pointed screws may be used for the purpose of adjusting the blade.

A small projection, n, is formed on the front of the rim C, for the purpose of giving the blade a central support, as shown in figs. 1 and 2.

The rim C also protects and shields the blade B from liability of being rapped or thrown out of place, while, at the same time, it stiffens and strengthens the handle A, so that the latter can be made much lighter than would otherwise be the case.

Having described my improvements in boot and shoe-shaves,

What I claim therein as new, and of my invention, and desire to secure by Letters Patent, is—

1. The conical-pointed adjusting-screws c, substantially as and for the purposes set forth.

2. The arrangement, in the handle A, of the blade B, and the holding-screws d, said screws being inserted from the front of the handle, so as to press against the shanks a, and cause the blade to take a direct bearing upon the handle, in the manner and for the purposes set forth.

3. A boot and shoe-shave, composed of the handle A, blade B, guard-plate E, holding-screws d, and adjusting-screws f and c, said parts being arranged to operate as shown and set forth.

SUMNER PACKARD.
